(57) **CLAIM**

The ornamental design for a vehicle grille, as shown and described.

DESCRIPTION

This invention was made with government support under DE-EE0007817 awarded by the U.S. Department of Energy. The government has certain rights in the invention.

FIG. 1 depicts a front, left, top perspective view of a vehicle grille showing our new design.

FIG. 2 depicts a front, right, bottom view thereof;

FIG. 3 depicts a front view thereof;

FIG. 4 depicts a right side view thereof;

FIG. 5 depicts a left side view thereof;

FIG. 6 depicts a back view thereof;

FIG. 7 depicts a bottom view thereof; and,

FIG. 8 depicts a top view thereof.

The ghosted or low contrasted portions of the vehicle grille illustrate portions that form no part of the claimed design. The dash lines depict boundaries of the claimed design.

1 Claim, 6 Drawing Sheets
